PARKING CANOPY

John Selby, 1350 Ghent Hills Road, Akron, Ohio

Filed June 27, 1961, Ser. No. 65,736

Term of patent 14 years

(Cl. D13—1)

FIG. 1

FIG. 2

FIG. 3

FIG. 4

FIGURE 1 is a perspective view of a parking canopy showing my design with a portion of one edge broken away;

FIGURE 2 is a side elevational view thereof;

FIGURE 3 is a top plan view thereof; and

FIGURE 4 is an end view thereof looking from the left of FIGURE 2.

The canopy is broken away in FIGURE 1 to indicate an article of indeterminate length.

The dominant features of the design reside in the portions shown in full lines characterized by tapering longitudinal members under the roof and the tapering vertical supports, the latter tapering downwardly and the former tapering outwardly from the vertical supports.

I claim:

The ornamental design for a parking canopy, as shown and described.
